UNITED STATES PATENT OFFICE.

THOMAS S. HOMANS, OF HEMPSTEAD, NEW YORK, ASSIGNOR TO THE INTERTYPE CORPORATION, OF NEW YORK, N. Y., A CORPORATION OF NEW YORK.

LINE-COMPOSING AND TYPE-CASTING MACHINE.

1,192,635.

Specification of Letters Patent. Patented July 25, 1916.

Application filed December 18, 1913. Serial No. 807,501.

To all whom it may concern:

Be it known that I, THOMAS S. HOMANS, a citizen of the United States, residing at Hempstead, in the county of Nassau and State of New York, have invented new and useful Improvements in Line-Composing and Type-Casting Machines, of which the following is a specification.

The present invention relates to improvements in typographic machines of the line-type class and more particularly to those of the type using a plurality of magazines holding a number of sets of matrices.

The primary objects of this invention are to provide improved means for bringing any one of the magazines into operative position to enable matrices therein to be used as desired and to provide means whereby a single distributing mechanism will serve to distribute matrices after use into the appropriate magazines irrespective of whether they are in operative or inoperative position.

In the preferred embodiments of the invention the distributor will maintain a fixed operative relation with the magazines, thus enabling matrices from the casting mechanism to be distributed into the appropriate magazines and permitting any one of the magazines to be brought into operative position, thus not only reducing the number of parts of the machine, but also enabling the machine to operate without interruption to the distribution of matrices to the different magazines.

To these and other ends, the invention consists in certain improvements, and combinations and arrangements of parts, all as will be hereinafter more fully described, the novel features being pointed out particularly in the claims at the end of the specification.

In the accompanying drawings: Figure 1 is a side elevation of a portion of a typographic machine embodying the present invention; Fig. 2 is a perspective view of portions of the framework thereof; Fig. 3 is a view similar to Fig. 1 but showing the parts shifted to bring a different magazine into operative position; Fig. 4 is a side elevation of the lower portion of the mechanism shown in Fig. 1, and showing in dotted lines the magazines swung into a position for removal; Fig. 5 is a front elevation of the construction shown in Figs. 1 and 3; Fig. 6

is a side elevation of the second elevator which transfers the matrices from the casting mechanism to the distributor, the dotted lines showing the elevator in two different positions to conform to the different positions which the distributor may occupy.

Similar parts are designated by the same reference characters in the several views.

The preferred embodiment of the invention is shown in the accompanying drawings and will be hereinafter described in detail. It is to be understood, however, that the invention is not restricted to the particular construction shown, as equivalent constructions within the scope of the claims may be used.

In the present instance, 1 designates parts of the main stationary frame of the machine which supports a transverse shaft 2. A pair of arms 3 are mounted on the shaft 2, these arms being adapted to swing or rock in a forward or backward direction about the shaft 2 as an axis. A pair of arms 4 extend above the arms 3 and have their lower ends pivoted to the arms 3 by the pivot pins 5. A beam 6 is fixed to or otherwise supported by the arms 4, and this beam is used to support the distributor. In the present instance, a distributor of the well known construction commonly employed in machines of this class is shown, it embodying a distributor bar 7 which is fixed to the beam 6 and is ribbed on its under side to support the matrices M and the distributor screws 8 which operate to feed the matrices along the distributor bar.

According to the present invention, different numbers of magazines can be used in each machine. In the present instance, the machine is adapted to hold two magazines 9 and 10, these magazines as shown having escapements 11 and 12 at the mouths thereof to prevent the discharge of matrices from the magazine not in use and to control, under the action of the keyboard, the delivery of matrices from the magazine which is in use. A single keyboard of the usual construction is preferably used to actuate the escapements of either magazine which is brought into operative position and thereby bring the matrices into use as desired. In Figs. 1 and 3, 13 represents one of the key rods of the keyboard which, in Fig. 1, is operative upon the magazine 10, and in Fig. 3 is operative upon the magazine 9.

The magazine 9 is fixed to a suitable frame 14 and the magazine 10 is fixed to a frame 15, these frames 14 and 15 being preferably secured together and provided toward their upper end with a pair of brackets 16 and toward their lower end with a bracket 17. The brackets 16 are pivotally suspended from a transverse rod 18, the ends of the latter being supported by a frame composed of a pair of arms 19 and a transverse tie rod 20. The arms 19 are mounted on the shaft 2 and are adapted to swing forwardly or rearwardly between the arms 3 and about the shaft 2 as an axis when it is desired to carry the magazines to or from the position shown by the dotted lines in Fig. 4 to enable the magazines to be changed. Ordinarily, however, the arms 19 and the arms 3 are united or connected as one part by pins 21 which are removably inserted in registering openings formed in overlapping lugs on the respective arms.

Guides are provided for conducting matrices from the distributor to the respective magazines. In the present construction, two sets of guides 22 and 23 are shown leading from the distributor to the magazines 9 and 10 respectively. The receiving ends of the two sets of guides preferably alternate beneath the distributor bar 7. To facilitate removal of the magazines when the latter are swung into the position shown by the dotted lines in Fig. 4, these guides are preferably carried by a frame or bracket 24 which is hinged to the magazine frame 15 at 25 whereby the frame or bracket 24 together with the guides may be swung into a position clear of the upper ends of the magazines as shown by the dotted lines in Fig. 4, thus enabling the magazines to be removed and others inserted with facility. A spring 26 is shown for holding the guides in operative or inoperative position. A roller 27 is mounted on one of the magazine frames and 45 is arranged to engage the under side of a foot 28, the latter being formed as a rearward extension on the lower end of the arm 4. This roller normally remains in constant engagement with the foot 28 and thereby 50 maintains the distributing mechanism in fixed operative relation with the magazines.

The bracket 17 toward the lower end of the magazine frame 15 is provided with a roller 29 which is arranged to coöperate with a cam 30. This cam is rotatably mounted on the shaft 2 and provided with a crank arm 31 which is connected by a link 32 to a crank 33, the latter being fixed to a shaft 34, this shaft being journaled in 60 suitable bearings 35 and 36 mounted on the stationary frame of the machine. A cam 37 is fixed to the shaft 34 and coöperates with a roller 38 mounted on a lever 39, the latter forming part of the swinging frame for the 65 magazines and is connected intermediately

to the tie rod 20 and at its opposite end engages the shaft 2.

40 represents what is known in machines of this class as the "intermediate" shaft, it being rotated constantly in an anti-clockwise direction, Fig. 1, and clutch-controlled means is provided between this shaft and the shaft 34. In the construction shown, a sliding clutch member 41 is splined on the intermediate shaft 40 and a companion clutch member 42 is mounted loosely thereon. A driving pinion 43 is connected to the clutch member 42 and coöperates with an intermediate gear 44, the latter being connected to an intermediate pinion 45 and this pinion coöperates with a driving gear 46 fixed to the shaft 34. A fork 47 is provided for shifting the clutch member 41 into and out of engagement with the clutch member 42, this fork in the construction shown being pivoted at 48 to the frame supporting the bearing 35 and the fork is operated by an arm composed of members 49 and 50 which are pivotally connected by a hinge 51, the member 49 being provided with a roller 52 which is arranged to be engaged alternately by the projections 53 located at diametrically opposite points on a collar 54 fixed to the shaft 34. A spring 55 operates to hold the roller 52 in the path of or in engagement with one of the projections 53 whereby the clutch is disengaged and held in disengaged relation against the action of the spring 56 which tends to engage the clutch. The roller 52, however, is provided with means for disengaging it from the co-operating projection 53 whereby the spring 56 may operate to engage the clutch. In the construction shown, an arm 57 is provided, the upper end of which is arranged to engage behind the pivoted member 49 and when moved forwardly it will operate to disengage the roller 52 from the co-operating projection. This arm 57 is pivoted at 58 and connected to a forwardly extending key lever 59, depression of the key lever operating the arm 57 to set the clutch into driving condition. When the shaft 34 has made a half revolution, the next or opposite projection 53 will engage the roller 52 and thereby automatically disengage the clutch. The arms 3 are preferably held yieldably in upright position or against movement in a rearward direction by plungers 60 which are pressed against the rear sides of these arms by springs 61.

Fig. 6 shows means for elevating the matrices after use from the casting mechanism to the distributor. As shown, 62 represents the intermediate channel through which the matrices are guided into engagement with the second elevator bar 63, the latter being pivoted at 64 to the end of the second elevator arm 65. The latter is pivoted to swing about a shaft 66 as an axis. A cam lever 67

67 is also mounted on the shaft 66 and carries a roller 68 which coöperates with the cam 69 which serves to raise and lower the second elevator arm. The second elevator 5 arm and the cam lever 67 are relatively movable and a spring 70 normally tends to separate them, the degree of separation, however, being limited by a connecting bolt 71. When the cam 69 operates upon the cam 10 lever 67 to raise the second elevator arm 65 until it reaches a limiting stop, which may be the beam 6, any further movement of the cam lever 67 under the influence of the cam 69 will cause yielding or compression of the 15 spring 70 and said spring possesses sufficient resilience to compensate for the different positions occupied by the beam 6.

According to the present invention, the distributor bears a constant relation to the 20 magazines irrespective of which magazine is in operative position, and it provides for the transfer of matrices from the casting mechanism to the distributing mechanism and from the latter to the different magazines whether the latter happen to be in 25 operative or inoperative position. Where, as in the present instance, the machine is adapted to hold two magazines, the parts will occupy the positions shown in Fig. 1, 30 when the magazine 10 is in use, and they will occupy the positions shown in Fig. 3 when the magazine 9 is in position for use. Assuming that the machine is in condition to use matrices from the magazine 10, as 35 shown in Fig. 1, the roller 38 on lever 39 will then rest upon the low part of cam 37, causing the arms 3, 4 and 19 to occupy their forward position, and the roller 29 will rest on the cam 30, the forward or lower ends of 40 the magazines being thereby supported with the magazine 10 in coöperative relation with the escapement actuating rods 13.

When it is desired to bring into use matrices contained in the magazine 9, the 45 key lever 59 is depressed, the arm 57 disengaging the roller 52 from the coöperating projection 53, and allowing the spring 56 to engage the clutch members 41 and 42 on the continuously rotating intermediate shaft 50 40. Rotary motion is then transmitted to the shaft 34, causing the latter to rotate a half revolution until the diametrically opposite projection 53 reaches the roller 52, whereupon the clutch just mentioned is disengaged. The shaft 34 turns the cam 37 55 in an anti-clockwise direction to first rock the magazine frames about the shaft 2, and the crank 33 then brings the came 30 into a position to allow the roller 29 to drop and thereby rock the magazine frames downwardly about the pivot rod 18. The first 60 cam action lifts the escapements of the magazine 10 clear of the escapement-actuating rods 13, and the subsequent cam action 65 brings the upper magazine 9 into the opera-

tive position previously occupied by the lower magazine 10. To bring the magazine again into operative position, the key bar 59 is depressed, whereupon the shaft 34 will make another half revolution in the same direction as before, and an action of the cams 37 and 30 (the reverse of that above described) will remove the magazine 9 from operative position and bring the magazine 10 into operative position. The magazines remain in fixed relation to the distributor irrespective of which magazine is in operative position and also during the movement of either magazine from operative position and the movement of the other magazine into operative position, and hence the distribution of matrices to either magazine may continue without interruption.

When it is desired to remove either or both magazines, the pins 21 are removed, thereby disconnecting the arms 19 from the arms 3, and the magazine frames with the entrance guides attached thereto may then be swung rearwardly about the shaft 2 as a center, as shown by the dotted lines in Fig. 4. The entrance guides may then be swung down underneath the magazine frames as shown in Fig. 4, thereby leaving an unobstructed passage for the removal of the magazines. Upon swinging the entrance guides and magazine frames back to normal position and replacing the pins 21, the magazines are restored to condition to be brought automatically into operative position as desired.

What is claimed is:

1. The combination of a plurality of magazines, each movable to and from operative position, a distributing device therefor, and movable supports whereby the distributing device is held in constant relative position to the magazines. 100
2. The combination of a plurality of magazines, each movable to and from operative position, a distributing device common to said magazines, and movable supports whereby said distributing device is held in constant relation therewith. 110
3. The combination of a plurality of magazines, each movable to and from operative position, a single distributor common to said magazines, and movable supports whereby said distributor is maintained in constant operative relation with said magazines. 115
4. The combination of a plurality of magazines shiftable alternately into operative position, a single distributor common to said magazines, and movable supports for maintaining it in constant operative relation therewith. 120
5. The combination with a plurality of magazines shiftable to bring different ones in operative position, distributor mechanism shiftable with the magazines, and an elevator for conveying matrices to the distribu- 125
- 130

- 4
- ter mechanism, said elevator being adapted to stop in different positions corresponding to the varying positions of the distributor mechanism.
- 5 6. The combination of a plurality of magazines shiftable bodily to bring any one of them into operative position, distributor mechanism shiftable with said magazines and having a constant relation therewith, 10 and an elevator for conveying matrices to the distributor mechanism, said elevator compensating automatically for the different positions occupied by the distributor mechanism.
- 15 7. The combination of a plurality of shiftable magazines, and a distributor common thereto and shiftable therewith into different positions, and an elevator for conveying matrices to the distributor and having yieldable operating means whereby it may stop in different positions according to the positions occupied by the distributor.
8. In combination, a pair of matrix containing magazines mounted on a movable 25 supporting frame, guiding means for said frame adapted to bring the magazines alternately into operative position, a power-driven member, and intermediate clutch-controlled connections between said power-driven member and the guiding means, the guiding means being operative to remove one magazine from operative position and to automatically position another magazine for operation.
- 35 9. In a machine of the class described, the combination with a pair of magazines each movable to and from operative position, means for removing one of said magazines from operative position and bringing 40 the other magazine into operative position upon each actuation thereof, power mechanism for actuating said means, and a stop device for automatically interrupting operation of said means when the latter has completed each actuation to position the desired magazine for operation.
10. The combination of a pair of magazines, means for alternately removing one magazine from operative position and bringing 50 the other magazine into operative position, means for bringing said magazines alternately into operative position by successive movements of said means in the same direction, mechanism for actuating said means, and a stop for automatically arresting 55 the movement of said means after each actuation thereof to position the desired magazine for operation.
11. The combination of a plurality of magazines, a movable frame supporting them, 60 means for shifting said frame to bring one or another of said magazines into operative position, a power-driven member, a clutch adapted to connect said member and said shifting means, manually operative means 65 for engaging said clutch, and automatic means for disengaging said clutch when the desired magazine reaches operative position.
12. The combination of a pair of magazines, means for bringing said magazines 70 alternately into operative position embodying a shaft having successive partial revolutions in the same direction, power mechanism for imparting successive partial revolutions to said shaft, and a stop for automatically arresting rotation of said shaft when the desired magazine reaches operative position.
13. The combination with escapement actuating mechanism, of a plurality of magazines, each carrying escapements and shiftable alternately into co-operative relation with said escapement actuating mechanism, means for shifting the magazines to remove one from such operative position and to 85 bring another into operative position, and a driving device for said means for operating the same in predetermined relation and embodying means for automatically arresting the operation thereof when the desired magazine 90 has reached operative position.
14. In a machine of the class described, the combination with a plurality of magazines, distributor means therefor, a swinging frame supporting the magazine, a swinging 95 support supporting the distributor, and means detachably connecting said swinging frame and support whereby any one of said magazines may be brought into operative position and the distributor maintained in 100 constant relation with said magazines, said swinging frame when disconnected from said support serving to carry the magazines into position for removal.
- In testimony whereof I have hereunto set 105 my hand in presence of two subscribing witnesses.

THOMAS S. HOMANS.
